US00D896295S

(12) **United States Design Patent** (10) **Patent No.:** **US D896,295 S**
(45) **Date of Patent:** **** Sep. 15, 2020**

(54) **VIDEO RECORDER FOR VEHICLE**

(71) Applicant: **THINKWARE CORPORATION**,
Gyeonggi-Do (KR)

(72) Inventor: **Hyun Ju Lee**, Gyeonggi-do (KR)

(73) Assignee: **THINKWARE CORPORATION**,
Gyeonggi-do (KR)

(**) Term: **15 Years**

(21) Appl. No.: **29/655,519**

(22) Filed: **Jul. 4, 2018**

(30) **Foreign Application Priority Data**

Jan. 4, 2018 (KR) 30-2018-0000677

(57) **CLAIM**

The ornamental design for a video recorder for vehicle, as shown and described.

DESCRIPTION

FIG. 1 is a perspective view of a video recorder for vehicle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof; and,

FIG. 7 is a bottom view thereof.

The broken lines in the drawings depict portions of the video recorder for vehicle that form no part of the claimed design.

1 Claim, 7 Drawing Sheets
